DRAWER GUIDE

Albert J. Ruckman, Mayville, N. Y., assignor to
 Chautauqua Cabinet Company, Mayville, N. Y.,
 a corporation of New York

Application February 12, 1941, Serial No. 378,603

4 Claims. (Cl. 45—77)

This invention relates to an improvement in guides for the drawers of articles of furniture such as chests, dressers, desks and the like.

The invention is particularly directed to a drawer guide structure for articles of furniture constructed from wood. Wooden furniture of the type more generally intended for use in the household, is manufactured according to standards somewhat different from those applicable to metal furniture. For instance, in metal furniture, drawer guides are required to be accurately and carefully designed so as to function properly under extreme use and considerable drawer load, and any noise involved in their operation, unless excessive, is of no particular importance. However, in wooden furniture of the type mentioned, drawer guides are generally required to sustain only moderate drawer loads and to be substantially noiseless in operation. Inasmuch as metal guides not only produce an objectionable noise in operation, but their cost of manufacture is disproportionate to an article of wooden furniture to which they might be applied, it is the common practice to utilize wooden drawer guides.

Wooden drawer guides are generally loosely fitted in order that the operative parts will not bind or become wholly inoperative due to changes in atmospheric conditions. Normally, when drawer guides of this nature are installed, the drawer is so loosely fitted that when withdrawn from its casing it will tend to stick, if pressure is applied at one corner or the other, and it may be stated that only when the parts have somewhat swelled or warped from their original shape do these guides function in a satisfactory manner, since only under these circumstances is the original looseness or play taken up.

It is the purpose of the present invention to provide a drawer guide having relatively movable parts that are closely fitted to eliminate substantially all side play of a drawer during movement from one position to another and this, therefore, constitutes one of the objects of the invention.

Another object of the invention lies in the provision of a drawer guide, the operative parts of which, although formed from material subject to distortion under changes in atmospheric conditions, will not impede or prevent movement of a drawer from one position to another.

Another object of the invention lies in the provision of a drawer guide, the parts of which are initially so fitted as to prevent side play of a drawer, and that will, even when distorted due

to atmospheric changes, function in the manner intended.

Another object of the invention lies in the provision of a single, centrally disposed guide for a drawer that, by reason of the interfitting parts, prevents lateral twisting or displacement of the drawer during its movement from one position to another.

Other and further objects of the invention will 10 be more fully understood and appreciated from a consideration of the following specification, taken in conjunction with the accompanying drawing; and in which

Figure 1 is a vertical transverse sectional view 15 of a part of an article of furniture, one or more drawers mounted on guides embodying one form of the invention;

Figure 2 is a front elevational view of a drawer, a part of the drawer head being broken away to disclose, in end view, the parts of the drawer guide embodying the invention;

Figure 3 is an enlarged side elevational view 20 of the drawer guide;

Figure 4 is an enlarged vertical sectional view 25 taken substantially on the line 4—4 of Figure 3; and

Figure 5 is a fragmentary perspective view of the parts of the drawer guide prior to assembly.

Reference is now had to the drawing wherein 30 the numeral 10 is employed to generally designate an article of furniture having one or more drawers mounted on guides embodying one form of the invention. The article includes conventional rear and side panels 11 and 12, top 13, and frame members 14. A drawer 16 is generally positioned between pairs of horizontally disposed frame members 14, the vertical spacing of which may be sufficient to receive the drawer front 17. The drawer includes the usual side and rear panels 18 and 19, together with a bottom panel 21. The bottom panel is generally somewhat above 35 the lower edge of the front 17, as indicated in the drawing.

A drawer guide, generally indicated by the numeral 22, comprises a pair of relatively movable elements 23 and 24. The element 23 is preferably attached to the under face of the bottom panel 21 and may be of sufficient length to extend from the front 17 to beneath the rear panel 19. The under face of the element 23 is formed with a longitudinally extending recess 26. This recess is formed by relatively shallow, vertical walls 27 that continue in inclined walls 28, which terminate in the recess base wall 29. The wall 29 is flat with the exception of a centrally dis-

posed, longitudinally extending rib 31. This rib projects downwardly into the recess and is formed with a curved surface, indicated at 32.

The other element 24 of the guide 22 is somewhat longer than element 23 and is notched at its ends, as indicated at 33. These notches are proportioned to interfit front and rear frame members 14, substantially as indicated in the drawing. That portion of the element 24 intended to interfit element 23 is formed with vertical side walls 34 that are comparable to the walls 27 of the other element. Above the walls 34, the element 24 is formed with a pair of longitudinally extending ribs 36 that, by reason of their spacing, produce a longitudinally extending recess 37. The ribs are formed with inwardly inclined walls 38 and top walls 39. At the meeting points of walls 34, 38, and 39 they are preferably rounded, as distinguished from the sharp meeting edges of walls 27, 28, and 29 of the element 23. It will also be noted that the walls of the recess 37 are straight surfaced as distinguished from the rounded surface 32 on the rib 31 of the element 23. The element 24 is permanently attached to the frame members 14 and the element 23 to a drawer and movable thereover.

Attention is now particularly directed to the purposes and advantages of constructing the interengaging parts of the guide in the manner described. Referring particularly to Figure 4, it will be noted that inclined walls 38 of element 24 contact the inclined walls 28 of the recess of the element 23 and it will be understood that the parts, as manufactured, are intended to contact in this manner. However, as has been brought out, the elements of the guide are formed from material that is subject to physical changes by reason of changes in atmospheric conditions. Thus, should a change in atmospheric conditions cause the elements to shrink, the element 24 would seat more fully in the recess 26 of the element 23, the upper rounded surfaces of the ribs 35, in part at least, contacting the base wall 29. On the other hand, should the change in atmospheric conditions cause the elements to swell, the element 23 would simply ride slightly higher on the inclined walls 38 of element 24. It will, therefore, be understood that regardless of changes in atmospheric conditions, the elements of the guide member are at all times sufficiently accurately interfitted to prevent appreciable side play in the drawer during movement from one position to another, and yet, the contacting elements of the guide member are sufficiently free so as to render them at all times relatively movable. Should either or both the elements of the guide member become slightly warped or distorted due to any change in atmospheric conditions, these elements will still function as intended, since such warpage or distortion will merely slightly shift the surface of contact without causing binding.

Although applicant has shown and described only one modification of his invention, it will be

understood that variations in the contour and size of the ribs and channels of the interfitting elements of the guide member may be made and are within the contemplation of the invention as set forth in the hereunto annexed claims.

Having thus set forth my invention what I claim as new and for which I desire protection by Letters Patent is:

1. A guide for operably mounting a drawer in an article of furniture comprising one element attached to said drawer and a second element attached to said article, walls defining a longitudinally extending recess in said one element, a rib projecting away from the base wall of said recess and dividing said recess in part into lesser recesses, a longitudinally extending pair of ribs on the second element, the ribs of the elements interfitting and maintaining the elements in operative alignment.

2. A guide for operably mounting a drawer in an article of furniture comprising a pair of elements, one of said elements being secured to said drawer and the other of said elements to said article, walls defining a lengthwise recess in one of said elements, certain of said recess walls being of converging incline, a rib projecting away from the base wall of said recess, a pair of lengthwise ribs on the other of said elements, the remote walls of said ribs being of a converging incline and adapted to contact the corresponding walls of said recess when said elements are assembled, the ribs of said elements interfitting to maintain said elements in operative alignment.

3. A guide for operably mounting a drawer in an article of furniture comprising a pair of elements, one of said elements being secured to said drawer and the other of said elements to said article, walls defining a lengthwise recess in one of said elements, certain of said recess walls being of converging incline, a rib projecting away from the base wall of said recess, a pair of lengthwise ribs on the other of said elements, said ribs being spaced to provide an area into which the rib of the first mentioned element projects, the remote walls of said pair of ribs being of the same converging incline as the certain walls of said recess and engageable therewith when said elements are assembled.

4. A guide for operably mounting a drawer in an article of furniture comprising a pair of elements, one of said elements being secured to said drawer and the other of said elements to said article, walls defining a lengthwise recess in one of said elements, the side walls of said recess being first parallel and then converging into a base wall, a lengthwise rib midway of and projecting away from said base wall, a pair of lengthwise ribs on the other of said elements, said ribs being spaced to provide an area into which the rib of the first mentioned element projects, the remote walls of said pair of ribs having the same contour as the side walls of said recess and being engageable therewith to provide operative contact for said elements.

ALBERT J. RUCKMAN.
